Primary Examiner — Paula Greene(74) *Attorney, Agent, or Firm* — Krieg DeVault LLP;
Clifford W. Browning(57) **CLAIM**

The ornamental design for a modern handleset, as shown and described.

DESCRIPTION

FIG. 1 is a top, right side perspective view of the modern handleset of the present invention.

FIG. 2 is a front view of the modern handleset of FIG. 1.

FIG. 3 is a right side view of the modern handleset of FIG. 1, the left side view being a mirror image thereof.

FIG. 4 is a top view of the modern handleset of FIG. 1; and, FIG. 5 is a bottom view of the modern handleset of FIG. 1.
